US00D934167S

(12) **United States Design Patent** (10) **Patent No.:** **US D934,167 S**
Van-Der-Veer (45) **Date of Patent:** **** Oct. 26, 2021**

(54) **ELECTRICITY CHARGING STATION FOR ELECTRIC VEHICLES**

(71) Applicant: **ABB Schweiz AG**, Baden (CH)

(72) Inventor: **Clemens Van-Der-Veer**, Zaandam (NL)

(73) Assignee: **ABB SCHWEIZ AG**, Baden (CH)

(**) Term: **15 Years**

(21) Appl. No.: **35/509,361**

(22) Filed: **Mar. 27, 2019**

(80) **Hague Agreement Data**

Int. Filing Date: **Mar. 27, 2019**

Int. Reg. No.: **DM/207794**

Int. Reg. Date: **Mar. 27, 2019**

Int. Reg. Pub. Date: **May 15, 2020**
